[57] **CLAIM**

The ornamental design for a circular shower stall, as shown and described.

DESCRIPTION

FIG. 1 is a perspective view of a circular shower stall showing our new design;

FIG. 2 is a front elevational view thereof;

FIG. 3 is a top plan view thereof;

FIG. 4 is a right-side elevational view thereof, the left side is a mirror image to that shown;

FIG. 5 is a sectional view along the line 5—5 of FIG. 2; and,

FIG. 6 is a sectional view along the line 6—6 of FIG. 5. The broken line showing is for illustrative purposes only, and forms no part of the claimed design.

FIG. 2**FIG. 3**

FIG. 4**FIG. 5****FIG. 6**
